UNITED STATES PATENT OFFICE.

CHARLEY MELLVILL FRANKLIN, OF GRISWOLD, IOWA.

COLLAPSIBLE CRATE.

Application filed October 3, 1924. Serial No. 741,483.

To all whom it may concern:

Be it known that I, CHARLEY MELLVILL FRANKLIN, a citizen of the United States, residing at Griswold, in the county of Cass 5 and State of Iowa, have invented new and useful Improvements in Collapsible Crates, of which the following is a specification.

My invention relates to collapsible or knock-down crates and its principal object 10 is to provide a crate of this character which when in knocked-down position will take up a minimum space and when set up for use will be rigid and durable.

A further object of the invention is to 15 provide a knock-down crate for shipping which can be quickly set up for use or knocked down and stored in a comparatively small space.

A still further object of the invention is 20 to provide a knocked down shipping crate which embodies a plurality of sections one of which is vertically movable and certain of which are hinged and arranged in operative position to support the vertically movable section in rigid position for use. When the crate is in knocked down position the vertically movable section will overlie the hinged sections and all of the same against accidental movement.

With the preceding and other objects and advantages in mind the invention consists 25 of the novel combination of elements, construction and arrangement of parts and operation to be hereinafter specifically referred to, claimed and illustrated in the accompanying drawings in which:

Figure 1 is a top plan view of the crate in a collapsed position;

Figure 2 is a side elevation of the same;

Figure 3 is an end elevation of the crate knocked down;

Figure 4 is a similar view showing the crate set up for use;

Figure 5 is a transverse sectional view of 45 the crate set up for use;

Figure 6 is a top plan view of the crate set up for use;

Figure 7 is a side elevation taken at right angle to Figure 4;

Figure 8 is a perspective of the vertically movable top section of the crate;

Figure 9 is a perspective of parts of the crate.

Referring to the drawings in detail 55 wherein corresponding characters of reference denotes the corresponding parts of the

several views the numeral 5 designates the bottom section of my improved crate while 6 designates a top or upper section.

Side walls or sections 7 are hingedly connected as at 8 to the bottom section 5 and when in use are arranged in the positions shown in Figures 4, 5 and 9, and when collapsed lie parallel to the bottom section as shown particularly in Figure 3.

Secured to the bottom section 5 at opposite sides thereof and at points outwardly from the adjacent hinged sections 7 are pairs of vertically extending posts 8 each of which is provided with a hinged joint 9 60 adjacent their lower ends. The longitudinal edges of the top sections 6 are provided with recesses 10 which slidably receive the vertically arranged posts 8. Straps 11 are secured to the longitudinal edges of the section 5 and bridge the recesses and serve to hold the strap sections against lateral shifting.

Stops 12 are carried by the upper ends of the posts 8 and adapted to be engaged by the straps 11 to limit the upward movement of the top section 6 when arranging with same in operative position. Shoulders 13 are also formed upon the inner faces of 70

these posts which accommodate themselves in inclined recesses 14 in the adjacent or 75 hinged sections 7 and engaged beneath the edges of the top sections 6 to assist in supporting the same in rigid position. Pairs of spaced feet 16 are secured to the upper 80

face of the sections 6 and extend transversely across the same. The cleats of each 85 pair are disposed at opposite sides of the recesses 10 and accommodate the posts 8 when the latter are arranged in a horizontal position as shown in Figure 2. In order to hold 90

the posts in position between the pairs of cleats latch elements 18 are provided to engage the free ends of the posts as shown in 95 Figure 1.

The top section 6 is provided with a longitudinal extended door opening 19 which is normally closed by a slide 20 received in guides 21 at the opposite ends of the top section and against longitudinal displacement by detachable fastenings 22. A partition wall 23 is provided for the crate and has its far edge pivoted as at 24 to bring about a horizontal axis to permit that this division wall be arranged in a horizontal position upon the section 5 when the crate 105 is collapsed.

In order to hold the hinged sections 7

which extend parallel to the division wall 23 in vertical position hasps 26 are pivoted to opposite ends of the section 5 and engageable in eyes 27 carried by these sections 7. When these hasps 26 are in inoperative position the free ends thereof are engaged behind vertical shafts 28 on the section 5 and are engageable with hook elements 27 carried by the upper ends of these sections 7 and in the eyes 28 carried by the opposite end of the top section 6. With the hooks 27 and eyes 28 in the manner shown in Figure 4 these hinged end sections 7 will be held in vertical position. When the hasps 26 are not in use they are arranged to extend along the sides of the outer edges of the bottom section 5 with their free ends engaged behind vertical shafts 29 carried by this section. From the disclosure it will be observed that when it is necessary to set up the crate the top section 6 is raised vertically on the posts 8 and the sections 7 swung to a vertical position and engaged below the edges of the section 6. In collapsing the structure the end walls are first swung inwardly to overlie the bottom section 5 and the top section 6 allowed to move downwardly to rest upon the sections 7. The posts 8 are then swung to a horizontal position to engage between the pairs of cleats 16 where they are locked against movement by means of the pivoted latch element 18, thus all the parts are rigidly held together and the entire assembly packed or stored in a small space.

While I have shown and described the preferred embodiment of the invention it

should be understood that changes in the arrangement of parts may be made and that I am only limited by the appended claims. 40

Having thus described the invention, I claim:

1. A knocked down crate comprising a bottom section, hinged sections carried by the bottom section and capable of being arranged in a horizontal or vertical position, a top section, guides carried thereby, hinged posts carried by the bottom section and slidably received in the guides, the posts being adapted to be arranged in a horizontal 50 position on the top section when the crate is collapsed, and latch elements engageable with the posts when the latter are arranged in such position whereby to hold all the parts against movement with respect to 55 each other.

2. A knocked down crate comprising a bottom section, hinged sections carried thereby capable of being folded upon the bottom section when not in use, hinged 60 posts carried by the bottom section and adapted to be arranged either in a vertical or horizontal position, a top section carried thereby and slidably receiving the posts and pairs of cleats on the top section each 65 pair of which being adapted to receive one of the posts therebetween when the latter are arranged in a horizontal position and latch elements carried by the sections and engageable with the posts to hold the same 70 in position.

In testimony whereof I affix my signature.

CHARLEY MELLVILL FRANKLIN.
